UNITED STATES PATENT OFFICE.

JAMES H. CUNNINGHAM, OF BROCKTON, MASSACHUSETTS.

BOOT AND SHOE.

No. 873,731.

Specification of Letters Patent.

Patented Dec. 17, 1907.

Application filed December 6, 1906. Serial No. 346,582.

To all whom it may concern:

Be it known that I, JAMES H. CUNNINGHAM, a citizen of the United States, residing at Brockton, in the county of Plymouth and State of Massachusetts, have invented a new and useful Improvement in Boots and Shoes.

In the wearing of boots and shoes having high heels great trouble has been caused by the breaking down of the shanks. This 10 breaking down is not only an injury to the shoe but a more serious injury to the feet of those wearing them.

The objects of my invention are to prevent these injuries by holding the shanks of shoes 15 in their original position; to preserve the proper shape of the shoes; to relieve the strain on the feet of the wearers so as to protect them from injury and to make elastic and comfortable shoes. I attain these objects by the devices herein described or shown in the accompanying drawings, and in Figure 1 represents a sole A showing a shank-piece B fastened on the upper or flesh side by rivets marked d. Fig. 2, shows a 20 longitudinal section of the same sole showing the rib C extending through the sole. Fig. 3 shows, an elevation, and Fig. 4 a transverse section, of the shank-piece B with the rib C. Fig. 5 exhibits a shoe having the shank-piece 25 in place between the outer and the inner soles, with the ribs C extending through the outer sole, shown along the line y y in Fig. 1.

After the outer soles intended for shoes have been cut into shape and prepared for 30 that part of the process of making shoes, called "bottoming", I attach a piece or shank of metal to the upper or flesh side of the sole. This shank-piece is made substantially in the form shown in Figs. 3 and 4. 35 marked B and is made preferably from some elastic metal, as brass, and is fastened permanently to the outer sole. This shank-piece is made with a rib on its under-side, which rib passes through the outer sole in an 40 opening marked F. The lower or outer side of the rib C, is made substantially in the form in which the shank of the shoe is made, i. e., the form of the arch of the rib is the proposed arch of the shank of the shoe. This 45 rib is inflexible and will hold the shanks of the shoes in a permanent position, so far as the rib extends. These ribs vary somewhat in length, generally from two and one-half to three inches for medium sizes of men's and 50 women's shoes, conforming to the length of 55

the shank pieces, which vary according to the size of the shoes.

All shoemakers will understand the reasons and the limits of these variations in length. The width of the shank-piece is 60 substantially the distance between the rows of sewing, or other fastening, which attach the outer soles to the inner soles or uppers of the shoe.

It will be noticed that the rounded end of 65 the shank-piece extends back in the shoe far enough to rest upon the heel, while it is intended to have the back end of the rib to start at the front of the heel.

While the rib C is made sufficiently stiff to 70 uphold the shank of the shoe and to support the shank of the foot, the other parts of the shank supporter are elastic and allow the shoe to be pliable to some degree, so as to be easy to the foot of the wearer. The shank 75 supporters are made long enough to extend under the heels, one end of the rib being placed against the front of the heel of the shoe, and to reach substantially to the point where the sole of the shoe will touch the 80 ground, but they must not be long enough to reach that part of the shoe which is called in the trade "the ball".

The shank pieces should never extend from the heels forward far enough to reach 85 the part of the outer soles which will touch the ground when on the feet of a person, and the ribs should extend only through the soles substantially to the outer or under sides of the outer soles.

90 The thickness of the shank-pieces should be such as will allow some elasticity as will be obvious to all those skilled in the trade of making shoes. The thickness and elasticity of the metal should vary somewhat, using 95 thicker metal for men's heavy shoes and thinner for light shoes, especially those for women and children. These shank-pieces are fastened in place in the shoes, especially in heavy shoes preferably by rivets through 100 the outer soles, as shown in Figs. 1 and 2, but it may not be necessary to use as many rivets as therein shown in light shoes. In some light shoes for women, the shank-pieces may be attached to the sole by other devices than 105 rivets, as by stitching or other common methods known in the trade.

110 While the shank-pieces will mostly be used in shoes having a substantial inner sole permanently attached to the outer soles, a light

grade of shank pieces may be used to advantage in thin shoes having no such inner soles, such as thin shoes for ladies; but even in these, an inner sole of some kind is commonly used.

It has been a common practice in shoe-making to place shank-pieces between the outer and the inner soles of shoes; but I do not know that shank-pieces, such as I have herein shown, having a rib passing through the outer soles and permanently attached thereto have ever been used before my invention.

What I claim and desire to secure by Letters Patent is:

1. A boot or shoe, having an outer sole

provided with a slot, a shank-piece upon the inner or upper side of said sole, and provided with a rigid rib lying in said slot and extending downward substantially flush with the outer or lower side of the outer sole.

2. A boot or shoe, having an outer sole provided with a slot extending from the breast of the heel, a shank-piece attached to the inner or upper side of the sole and provided with a rigid rib lying in said slot, and extending downward substantially flush with the outer or lower side of the outer sole.

JAMES H. CUNNINGHAM.
